UNITED STATES PATENT OFFICE

HAROLD DONALD WELLS, OF GLENS FALLS, NEW YORK

PAPER STOCK REGULATOR

Application filed May 22, 1930. Serial No. 454,703.

The principal object of this invention is to regulate or rectify the consistency of paper stuff more uniformly and more accurately than present machines.

5 Another object is to regulate to uniformity instantly and accurately large variations in consistency of stuff, and at the same time record this work on a recording gauge.

Another object is to provide a simple and 10 effective stuff regulator; eliminating troublesome motor, reduction gears, ratchet and pawl, delicate weighing scales, orifice which often clogs, cylinder which often gets dirty and upsets regulation, motor driven agitator, 15 conical orifice, and other troublesome features; thus providing a regulator which is rugged, which gives dependable operation requiring no attention.

Another object is to provide a regulator 20 which is applicable to all kinds of paper stock, which can be quickly and easily changed from one order to the next; one which has a greater range than others operating on a thicker or thinner stock.

Another object is to provide a regulator which produces uniform consistency stuff and accurately regulates or rectifies stuff in various parts of paper mills, etc.; such as at paper machines, at jordans, at mixers and proportioning machines, at board machines, at pulp machines, at screens, at bleachers and the like; which can produce uniform thin stock for screens.

Another object is to provide a regulator in which all "hunting" is eliminated.

With these and other beneficial objects in view, I now describe this invention with reference to the accompanying drawings in which:—

Fig. 1 is a top plan view of a regulator constructed in accordance with my invention.

Fig. 2 is a vertical sectional view on line 2—2 of Fig. 1.

Fig. 3 is a vertical sectional view on the plane of line 3—3 of Fig. 1.

Fig. 4 is a diagrammatic sectional perspective view of the tank and the means by which it is partitioned into the various chambers and passages hereinafter described.

Fig. 5 is an enlarged vertical sectional view through the water admission valve.

The preferred construction has been illustrated and while such construction will be herein specifically explained, it is to be understood that within the scope of the invention as claimed, numerous variations may be made.

The numeral 6 denotes a rectangular box or tank whose interior is partitioned in a manner hereinafter described, to provide an initial stock-receiving chamber 7, a constant-level water chamber 8, a stock-rectifying chamber 9, a stock-receiving control chamber 10, an outlet passage 11 from the rectifying chamber 9, a discharge passage 12 from the control chamber 10, a water chamber 13 under the constant level chamber 8, water-conducting means 14—15 from the chamber 13 to the rectifying chamber 9, and a stock-conducting 60 passage 16 from the initial stock-receiving chamber 7 to said rectifying chamber 9. The passage 16 embodies a vertical dam 17 over which the stock spills into the rectifying chamber 9, and the passage 15 embodies a vertical dam 18 over which the water spills into 65 said chamber 9, the upper end of said dam 18 being provided with a flange 19 which substantially overlies the dam 17. These two 70 dams are so positioned that the stock and water spill over them in sheets and these 75 sheets contact with each other insuring thorough mixing.

The chamber 8 is provided with a water inlet 20 (Fig. 1) controlled by a float-actuated valve 21 within said chamber, said valve 21 serving to maintain a constant water level within this chamber. The bottom of the chamber 8 is provided with a water outlet 22 controlled by a valve 23, this valve being 80 actuated in a manner hereinafter described.

The initial stock-receiving chamber 7 is provided with a stock inlet 24 having a valve 25, this valve being connected by appropriate 85 operating means such as rod 26 and lever 27, with a float 28 in the rectifying chamber 9. The outlet passage 11 from this chamber, is 90 formed with two openings 29 and 30 controlled by gates 29' and 30' respectively, the opening 29 being in communication with the 100

control chamber 10 while the opening 30 is in communication with a main discharge 31 from the entire apparatus. The discharge passage 12 from the control chamber 10 leads 5 to this passage 31 and a pivoted gate 32 which is adjustable by appropriate means 33, is employed for varying the conducting capacity of said discharge passage 12.

A stock-raised float 34 is disposed within 10 the control chamber 10 and is connected by a rod 35 with a toggle 36 suitably mounted in the upper portion of the tank 6, said toggle being connected by a link or the like 37 with the valve 23.

15 A recording meter 38 is suitably mounted upon the tank and embodies the conventional rotatable disk co-acting with two pens 39 and 40. Pen 39 is operatively connected by appropriate means 41 with the toggle 36 and is 20 operated by this toggle incident to operation of the valve 23 to show the consistency of the stock before regulation. The pen 40 is connected by a rod 42 with a float 43 within the control chamber 10 and is actuated by said 25 float to show the consistency of the stock after regulation. The manner in which the two pens indicated at 39 and 40, show the stock consistency before and after regulation, will be hereinafter more fully explained.

30 The paper stuff or stock enters the regulator from the inlet 24 when the valve 25 is opened, and from the initial stock-receiving chamber 7, the stock passes through the passage 16 and spills over the dam 17 into the rectifying chamber 9, and when float 28 in said 35 chamber 9 has risen to a predetermined extent, it operates the connections 27 and 26 to close said valve 25. Much of the stock passes from the rectifying chamber 9 and its outlet 40 11, through the gate-controlled opening 29 into the control chamber 10, and the remainder passes through the gate-controlled opening 30 directly into the main discharge 31 from the apparatus. The quantity of stock 45 passing through the opening 29 into the control chamber 10, is a little less than the minimum requirements, and is maintained constant. The quantity passing through the opening 30 is the remainder necessary to produce the weight for the order, and the gate 50 30' which controls this opening 30 is adjustable from one order to the next, to meet the requirements of weight. The stock passing through the opening 29 travels around a baffle 55 45 into the control chamber 10 and takes substantially the course illustrated by the arrows in Fig. 4, passing out through the discharge passage 12 whose carrying capacity has been properly adjusted by inward or outward 60 shifting of the gate 32. The stock passing through passage 12 flows to the main discharge 31, mingling with that which was discharged through the opening 30. Gate 32 is 65 adjusted toward closed position until the stock level in the control chamber 10 may rise

to the proper height, causing float 34 and the operating connections 35-36-37 to open the water admission valve 23. Upon each opening of this valve, water from the chamber 8 enters the chamber 13 and then passes through the water-conducting means 14-15 into the rectifying chamber 9, said water spilling over the dam 18 and mixing with the stock passing over the dam 17. The regulated water mixing with the stock in the chamber 9, brings the latter to the desired consistency.

The stock possesses definite friction values at various consistencies and this friction acts upon the gate 32. As long as the stock remains uniform, there is no movement of regulator parts, but when the stock becomes somewhat thicker, it cannot flow as rapidly through the outlet 12 from the chamber 10, with the result that the level rises in said chamber. This rising of the stock level, raises the float 34 and causes opening of the water admission valve 23 to admit the proper amount of water to bring the stock back to normal consistency. When thinner stock is received in chamber 10, it can more readily escape from said chamber with the result that the float 34 then drops slightly, causing closing of the water admission valve 23 to the proper extent. The construction of the regulator is such that changes in consistency are immediately rectified and the level in the chamber 10 changes only minutely. Thus, the stock discharging from the apparatus through the main discharge 31, is uniform in consistency and uniform in quantity.

With further regard to the pens or indicators 39 and 40, attention is invited to the following:—The operation of the water valve 23 is relative to the consistency of stock before regulation, as the regulator valve is operated relative to variations of stock, to bring the latter to uniformity. Hence, the indicator or the like 39 shows the consistency of the stock before regulation, being actuated by a part of the operating means for the regulating valve 23. As the pointer or the like 40 is controlled by the float 43 which rides upon the surface of the regulated stock in the control chamber 10, it shows the consistency of the stock after regulation.

Attention is invited to the fact that the admission of water (or other liquid) to the mixing or rectifying chamber 9, is dependent upon the travel of regulated or rectified stock through the control chamber 10, in which the water valve float 34 is located. The stock enters the control chamber 10 through the opening 29 and leaves through the passage 12, and in order that the flow shall take place in the required manner without undue fluctuation, it is necessary to maintain a substantially constant head of stock above said opening 29. Due to the construction of the present invention, this head is maintained in the chamber 9, and hence a constant level

chamber heretofore required for the purpose of maintaining the required head above the inlet of a control chamber analogous to chamber 10, is dispensed with, the function 5 of the constant level chamber however, being retained and assigned to the chamber 9.

Further attention is invited to the fact that whereas stock regulation has heretofore been controlled by automatic operation only of a 10 liquid valve which admits liquid to a rectifying or mixing chamber, I automatically control both a liquid admission valve and a stock admission valve, the one being moved toward open position when the other is moved toward closed position, and vice versa. By so doing, I attain unusually quick stock rectification or regulation, bringing the stock almost instantaneously back to normal as soon as its consistency fluctuates one way or the 20 other. To illustrate, if abnormally thick stock enters the chamber 9, it rises somewhat in said chamber 9, and this slightly increases the head above the control chamber inlet 29, with the result that the stock enters the 25 control chamber 10 somewhat more rapidly. At the same time, due to friction of the relatively stiff stock against the gate 32, said stock leaves chamber 10 with less rapidity. These factors cause rise of the stock level somewhat in the chamber 10. The rise in the chamber 9 operates float 28 to partially close the stock admission valve 25, and the rise in chamber 10 operates float 34 to move the water valve 23 further toward open position, 35 or from closed to partly open position should said valve stand closed. By thus diminishing the admission of stock and admitting or increasing the admission of water at the same time, the stock is brought back to normal consistency with unusual rapidity, in fact, almost instantaneously with the slightest rise in said chambers.

Provision is made whereby the valve 23 is 40 prevented from "hunting", that is, said valve is prevented from letting in too much water and then cutting off too much. In attaining this end, the construction detailed in Fig. 5 is employed.

A ring 46 is secured upon the bottom 47 of 45 the constant-water-level chamber 8, around the opening 22 thereof, the inner periphery of said ring being provided with a downwardly facing valve seat 48. An upwardly opening dash pot 49 is disposed below the ring 46, 50 within the chamber 13, said dash pot being provided with upstanding arms 50 secured to the ring 46 and hence supporting said dash pot. The lower end of this dash pot is provided with a restricted, regulable port 51 which controls discharge of water into the 55 chamber 13 from the dash pot, and entrance of water into said dash pot from said chamber. The valve 23 is cooperable with the seat 48 and is provided with a plunger 52 operable 60 within the dash pot 49. In order that this

valve may lower to admit water to the rectifying chamber 9, it must first displace water through the port 51 from the dash pot 49. Similarly, in order to partially or totally close, the valve must draw water into the dash 70 pot 49 through the port 51. Hence, the movement of the valve is so controlled that it is prevented from "hunting".

The float-controlled valve 21 in the chamber 8, may be of any desired construction and constitutes no part of the present invention. Obviously, this valve and all other parts of the apparatus may be constructed from any materials suitable to the purposes for which they are designed and the conditions which must be met. It may also be stated that although the tank 6 may be partitioned in any of various ways to provide the structural characteristics hereinbefore described, the specific partitioning which has been illustrated is preferably employed, such partitioning being now described in detail.

A main vertical partition 53 rises from the bottom of the tank 6 and extends between two opposed sides of said tank. At one side of this partition, is another vertical partition 54 which assists in forming the chambers 8 and 13, these two chambers being separated by the bottom 47, above mentioned. At the side of the partition 54 opposite the chambers 8 and 13, is the chamber 10, the baffle 45 of this chamber being secured to the partition 53. The chamber 9 is at the opposite side of the partition 53 from the chamber 10, being formed in part by said partition 53, partially by the dam 17 which is secured to said partition 53 and to one of the side walls of the tank 6, and partially by a horizontal partition 55. This partition 55 forms the bottom of the chamber 9 and the top of the chamber 7. The passage 16 is formed between the dam 17 and the dam 18, and the latter also co-acts with the partition 53 and adjacent walls of the tank 6, in forming the passage 15, the partition 53 being provided with the notch 14 which places said passage 15 in communication with the chamber 13. The lower end of passage 15 is closed by directing the dam 18 outwardly and securing it against the adjacent vertical side of the tank.

In opposed relation with the dam 17 and spaced inwardly from one side of the tank 6, is a substantially L-shaped vertical partition 56 which is secured to the end of the horizontal partition 55 remote from said dam 17. This partition 56 forms one wall of the rectifying chamber 9 and one wall of the initial receiving chamber 7 and the notch 57 of said partition 56, places chamber 9 in communication with the vertical outlet passage 11. This passage is formed partly by the partition 53 and partly by a vertical partition 58 parallel with said partition 53 and extending from partition 56 to the adjacent side wall of the tank 6. Opening 30 is formed in the 120

lower end of partition 58 and opening 29 is opposite said opening 30 being formed in the partition 53. Secured under the partition 58 and the opposed portion of the partition 53, is a horizontal partition 59 which forms the lower end of the passage 11 and also forms the top of the discharge passage 12, the inner edge of this partition 59 being secured to the lower portion of the partition 56 and to the 10 baffle 45, while the outer edge of said partition 59 is secured to a side wall of the tank 6. The gate 32 operates between the tank bottom and the partition 59 and contacts with both of them.

15 The various partition members and the like may be soldered, welded or otherwise secured in such relation as to jointly form the various chambers, passages, etc.

I claim:—

20 1. A stock regulating apparatus comprising a stock-rectifying chamber, stock-conducting means leading to said rectifying chamber and embodying a stock valve, water-conducting means leading to said rectifying chamber and embodying a water valve, a stock-raised float in said rectifying chamber and means connecting said float with said stock valve for controlling the latter, a stock-receiving control chamber and a passage leading thereto from said rectifying chamber, a stock-lifted float in said control chamber and means connecting this float with said water valve to control the latter, and a discharge passage leading from said control chamber.

25 2. A stock regulating apparatus comprising a constant level water chamber having a float-controlled water inlet valve and a water outlet valve, an initial stock-receiving chamber having a stock inlet valve, a stock-rectifying chamber, means for conducting water and stock to said rectifying chamber from said water outlet valve and said initial stock-receiving chamber respectively, a stock-raised float in said rectifying chamber and means connecting said float with said stock-inlet valve to control the latter, a stock-receiving control chamber and a stock-conducting passage leading thereto from said rectifying chamber, a stock-lifted float in said control chamber and means connecting this float with said water outlet valve to control the latter, and a discharge passage leading from said control chamber.

30 3. A stock regulating apparatus comprising a stock-rectifying chamber, stock-conducting means leading to said rectifying chamber and embodying a stock valve, water-conducting means leading to said rectifying chamber and embodying a water valve, a stock-raised float in said rectifying chamber and means connecting said float with said stock valve for controlling the latter, a stock-conducting passage leading from said rectifying chamber and having two outlets, a main discharge from the entire apparatus with

which one of these outlets communicates, a stock-receiving control chamber into which the other of said outlets discharges, a stock-raised float in said control chamber and means connecting this float with said water valve for controlling the latter, and a discharge passage leading from said control chamber to said main discharge.

35 4. A structure as specified in claim 3; together with means for varying the conducting capacities of said two outlets and the discharge passage leading from the control chamber.

40 5. A structure as specified in claim 1; said stock-conducting means and said water-conducting means embodying two closely related dams, said dams being positioned to cause spilling of the stock and water over them into the rectifying chamber in contacting sheets.

45 6. A stock regulating apparatus comprising a single tank, partitioning means dividing said tank into a constant level water chamber, an initial stock-receiving chamber, a stock-rectifying chamber, a stock-conducting passage from said initial stock-receiving chamber to said rectifying chamber, a water-conducting passage leading to said rectifying chamber, a stock-outlet passage from said rectifying chamber, a stock-receiving control chamber, and a discharge passage from said control chamber; means for maintaining a constant water level in said water chamber, a stock-admission valve for controlling entrance of stock into said initial stock-receiving chamber, a water-regulating valve for controlling communication between said water chamber and said water-conducting passage, operating means for said stock-admission valve embodying a float in said rectifying chamber, operating means for said water-regulating valve embodying a float in said control chamber, two gates one of which controls communication between said stock-outlet passage and said control chamber, the other gate controlling communication between said stock-outlet passage and said discharge passage, and means for regulating the carrying capacity of the latter.

50 7. A structure as specified in claim 6; said partitioning means embodying closely related dams forming portions of said water-conducting passage and said stock-conducting passage, said dams being positioned to cause spilling of the water and stock over them into the rectifying chamber in contacting sheets.

55 8. In a stock regulating apparatus, a stock receiving and rectifying chamber, a control chamber and means placing it in communication with said rectifying chamber, means for conducting liquid to said rectifying chamber including a valve, a stock-actuated member in said control chamber, and inter-connected motion-transmitting means directly connected with said stock-actuated member and directly connected with said valve for directly

transmitting movements of said stock-actuated member to said valve.

9. In a stock regulating apparatus, a stock-receiving and rectifying chamber, a control chamber in communication therewith, a water chamber having an outlet valve through which the water discharges by gravity, a dash-pot for controlling the speed at which said valve opens and closes, means for conducting the water from said valve to said rectifying chamber, said means containing said dash-pot, a stock-raised float in said control chamber, and means connecting said float with said valve for controlling the latter.

15 10. In a stock consistency regulating apparatus, a control chamber which receives the regulated stock, said chamber having an outlet provided with means for varying its conducting capacity, and liquid supply means 20 for the stock having an operating member actuated by rise and fall of stock in said chamber.

11. In a stock regulating apparatus, an initial stock-receiving chamber having a stock 25 inlet, a stock-rectifying chamber and means for conducting the stock from said initial chamber to said rectifying chamber, a valve for said stock inlet, a float in said rectifying chamber, and means connecting said float with said valve for controlling the latter.

12. In a stock regulating apparatus, stock-controlled valve mechanism for admitting water to the stock to regulate its consistency, indicating means operatively connected with 35 and actuated by said valve mechanism for showing the consistency of the stock before regulation thereof, and additional stock-controlled indicating means for showing the consistency of the stock after regulation.

40 13. In a stock regulating apparatus, a stock receiving and rectifying chamber, a control chamber and means placing it in communication with said rectifying chamber, means for conducting water to said rectifying chamber 45 embodying a valve, a stock raised float in said control chamber, valve-actuating means connecting said float with said valve for controlling the latter, and indicating means connected with and operated by said valve-actuating means for showing the consistency of the stock.

14. In a stock regulator, stock receiving and conducting means, stock and liquid admission means for said stock receiving and 55 conducting means including stock and liquid valves, and means controlled by the stock in said receiving and conducting means for moving the stock valve toward closed position and the liquid valve toward open position upon 60 reception of abnormally thick stock in said conducting means and vice versa.

15. In a stock regulator, a stock and liquid mixing chamber through which stock flows continuously, a control chamber through 65 which a sample of the stock is continuously

shunted from said mixing chamber, and admission means for said mixing chamber including liquid and stock valves, and operating means for said valves having stock controlled actuating members, one of said actuating members being in said mixing chamber and the other in said control chamber.

70 16. In a stock regulator of a type in which admission of liquid to a stock-conducting mixing chamber is dependent upon flow of regulated stock through a control chamber which receives the stock by gravity from said mixing chamber; a valve for controlling stock admission to said mixing chamber, and means actuated by rise and fall of stock in said mixing chamber for operating said stock admission valve; whereby the last named means is instrumental in regulating the stock and in maintaining a substantially constant head above the inlet through which said control 80 chamber receives the regulated stock.

75 17. In a stock regulator, a stock and liquid mixing and conducting chamber having at least two gravity outlets, a control chamber which continuously receives regulated stock from one of said outlets, said control chamber also having a gravity outlet, means actuated by the stock in said control chamber for controlling admission of liquid to said mixing chamber, and means including a stock-actuated member in said mixing chamber for controlling the admission of stock to the latter, the stock regulation effected by said admission of stock and liquid serving to maintain a substantially constant head above said one of 100 said mixing chamber outlets.

In testimony whereof I affix my signature.
HAROLD DONALD WELLS.
